UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

APPARATUS FOR USE IN ATTACHING HEELS.

Application filed January 25, 1923. Serial No. 614,803.

To all whom it may concern:

Be it known that I, FREDERIC E. BERTRAND, a citizen of the United States, residing at Lynn, in the county of Essex and State 5 of Massachusetts, have invented certain Improvements in Apparatus for Use in Attaching Heels, of which the following description, in connection with the accompanying drawings, is a specification, like reference characters on the drawings indicating 10 like parts in the several figures.

This invention relates to attaching heels to shoes, and is illustrated as embodied in improved means for use in clamping a heel 15 against the heel seat of a shoe while the heel-attaching adhesive is drying.

In my co-pending application Serial No. 561,901, filed May 18, 1922, there is described apparatus for clamping heels to 20 lasted shoes by passing a headed screw fastening through a perforation in the rear end of each last and through the heel seat of the shoe into the heel, in such a manner as to clamp the last and shoe and heel together. An object of the present invention 25 is to provide for clamping heels in a generally similar manner to shoes from which the lasts have been removed without rendering it necessary to replace the last in 30 the shoe.

From this point of view the invention may be regarded as contemplating the use 35 of blocks, each of which has a surface shaped to engage and transmit pressure to the inside rear bottom surface of a shoe, opposite the heel seat, and each of which is formed with a reduced portion having fastening-receiving hole or perforation, said reduced portion being adapted loosely 40 to be received within a shoe so that ample clearance will be provided for the convenient introduction and removal of the block and adapted wholly to be contained within the shoe so that it will not interfere with 45 the free manipulation of the shoe in the performance of finishing operations thereon while the heel is temporarily clamped to the shoe by the screw fastening. Preferably a pressure-receiving portion, used in clamping 50 the block against the shoe and heel while inserting the fastening, is arranged to receive pressure directed perpendicularly toward said surface, in such a manner that the pressure may be applied without obstructing the fastening-receiving hole. A

thimble hole may be provided, if desired, to receive the usual jack pin, in supporting the shoe on a rack or for other purposes.

Other objects and features of the invention, including the specific construction of 60 the blocks, and a novel heel-supporting device, will be apparent from the following description of an illustrative embodiment of the invention shown in the accompanying drawings, in which:

Figure 1 is a side elevation, showing the work partly in section, of a block and a shoe and a heel clamped together and resting on the novel heel-supporting device;

Fig. 2 is a top plan view of the assembly 70 shown in Fig. 1 without the shoe; and

Fig. 3 is a side elevation of a modified form of block and a correspondingly modified form of pressing member.

As shown in the drawings, the novel block 75 10 is held assembled with a shoe 12 and a heel 14, in a machine generally like that of my prior application, by the clamping action of a support 16 and a pressing member 18. While the block and shoe and heel are 80 so held, and after a hole is drilled through the heel seat of the shoe into the heel, a screw fastening 20 is passed through a hole or perforation 22 in the block and through the heel seat of the shoe into the heel. The 85 screw fastening 20 comprises a screw-threaded shank carrying one or more washers 24 of leather or other resilient material and one or more metal washers 26, the shank being looped at one end into the form of an 90 eye. The washers 24 and 26, together with the looped end of the screw shank, may be regarded as constituting the head of the fastener. Clamping pressure is transmitted 95 from the looped end of the fastening through the one or more resilient washers 24 and the metal washers 26. After the drying of the heel-attaching adhesive, fastening 20 and block 10 are removed.

A notch 28 may be formed in the block 100 10 to receive the pressing member 18 without permitting it to slip, and without obstructing the hole through the block. Or if preferred, a thimble hole 30 may be formed in the block to receive a jack pin, and a 105 steel wear plate 32 may be provided to be engaged by a toothed pressing member 34 (Fig. 3). Prongs 36 are carried by the bottom of the block, to prevent slippage.

The top of a heel is almost invariably 110

concave, and the bottom of block 10 is formed substantially plane, so that the maximum pressure is localized in a narrow area about the periphery of the heel and 5 shoe, closing any gaps in the rand crease and producing a very close fit. The bottom flange 38 of the block is of a general D shape, corresponding to the shape of the inside rear bottom surface of a shoe.

10 The improved support 16 shown in the drawings comprises a base 40 having a post 42 to be clamped in the frame of the machine shown in my prior application, and having a surface 44 to engage the tread surface of a heel. At the center of its rear end 15 a sleeve 46 is formed, in which is clamped by set screw 48 a post 50 carrying a leather, rubber, or felt insert 52 to engage and support the rear surface of the heel.

20 Sleeves 54 are formed at opposite sides of the support, in each of which is clamped by a set screw 56 a shaft 58. Each shaft 58 serves to support a U-shaped arm 60 having a pair of bearings 62 turning on opposite 25 ends of the shaft. These arms are urged toward one another by a spring 64 as far as permitted by an adjustable stop 66 carried by one of the arms. The end of each arm 60 is formed as a split clamp, in which 30 is adjustably held a vertical post 68 having a heel-engaging insert 70.

In operation, a block 10 and shoe 12 and 35 heel 14 are held assembled together by supporting the heel on the support 16 and applying pressure through member 18, a hole is drilled through the heel seat of the shoe into the heel in alignment with hole 22, and a fastening 20 is inserted and driven home. The shoe may now be handled and treated 40 in any desired manner, the block and shoe and heel being held clamped together by fastening 20. After the heel-attaching adhesive has dried, fastening 20 and block 10 are removed, the heel nailed, and the shoe 45 finished in any desired manner.

While specific embodiments of my invention are illustrated and described, it is not my intention to limit its scope thereby or otherwise than by the terms of the appended 50 claims.

I claim:

1. A unitary block for use in attaching heels to shoes from which the last has been withdrawn having a surface shaped to engage and transmit pressure to the inside bottom surface of a shoe at the heel end only, a portion to receive pressure from a clamp member arranged substantially perpendicularly above the central part of said surface, and a fastening-receiving perforation opening at one side of the pressure-receiving portion at one end and substantially at the center of said surface at the other end, the block being shaped to provide ample clearance between the block and the shoe upper 65

at all points above the bottom of the shoe.

2. A block for use in attaching heels having a generally D-shaped bottom surface shaped to engage and transmit pressure to the peripheral edge of the inside bottom surface of a shoe opposite the heel seat, a portion constructed and arranged to receive pressure from a clamp member directed toward said surface, a cylindrical hole opening at one side of the pressure-receiving portion at one end and within said surface at the other end for receiving a headed fastener, and a surface at right angles to the length of the hole to provide a seat for the head of the fastening. 75

3. A block for use in attaching heels having a generally D-shaped bottom surface constructed and arranged to engage the inside rear bottom surface of a shoe and to transmit clamping pressure thereto localized about the periphery, a reduced portion adapted loosely to be received and wholly contained within the shoe, and having a fastening-receiving hole extending through said reduced portion and opening substantially 85 at the center of said surface. 90

4. A block for use in attaching heels having a surface to engage and transmit clamping pressure to the inside rear bottom surface of a shoe, and a reduced portion adapted loosely to be received and wholly contained within a shoe, the block having also a fastening-receiving hole extending through said reduced portion and opening at its bottom within said surface and a thimble hole in 95 said reduced portion to receive a supporting pin. 100

5. A block for use in attaching heels having a surface to engage and transmit clamping pressure to the inside rear bottom surface of a shoe, and a reduced portion adapted to be received and wholly contained within a shoe and to be spaced inwardly from the shoe upper, the block having also a fastening-receiving hole extending through said reduced portion and opening at its bottom within said surface, a thimble hole to receive a supporting pin, and a portion to receive pressure directed toward said surface without obstructing the top of said fastening-receiving hole. 110 115

6. A block for use in attaching heels having a surface to engage and transmit pressure to the inside rear bottom surface of a shoe and a portion constructed and arranged to receive a clamping member and to locate said member in a predetermined relation to said block and said block being constructed and arranged to be detachably engaged by a fastening passing through the heel seat of the shoe into a heel in such a manner as to maintain said pressure. 120 125

7. A block for use in attaching heels having a surface to engage and transmit pressure to the inside rear bottom surface of a 130

shoe, and prongs to prevent the block from slipping, said block being constructed and arranged to be engaged detachably by a fastening passing through the heel seat of the shoe into the heel for clamping the shoe and the heel and the block together and being shaped to provide ample clearance between the block and the shoe upper.

8. A heel holding device comprising, in combination, a tread support, a member vertically-adjustable relatively to the support to engage the rear surface of a heel, arms carried by said support, side-engaging members carried by said arms and vertically ad-

justable relatively thereto, a spring urging 15 said arms toward one another, and a stop to limit the movement of the arms.

9. A heel-holding device comprising, in combination, means for supporting a heel in upright position by engagement with its 20 tread face, a member to engage the rear surface of a heel supported on said means, and members vertically adjustable relatively to said supporting means to engage opposite side surfaces of the heel. 25

In testimony whereof I have signed my name to this specification.

FREDERIC E. BERTRAND.
